(57) **CLAIM**

I claim the ornamental design for an anti-flood barrier, as shown and described.

DESCRIPTION

FIG. 1 is a perspective view of an anti-flood barrier in a deflated condition.

FIG. 2 is a front view of the anti-flood barrier shown in FIG. 1.

FIG. 3 is a perspective view of the anti-flood barrier shown in FIG. 1 in an inflated condition.

FIG. 4 is a front view of the anti-flood barrier shown in FIG. 1 in an inflated condition; and,

FIG. 5 is a perspective view of the anti-flood barrier shown in FIG. 1 in an inflated condition with handles extended.
